UNITED STATES PATENT OFFICE.

HILDEBERT VAN BUREN, OF PHILADELPHIA, PENNSYLVANIA.

COMBINED GAS-BURNER AND WATER-HEATER FOR RANGES.

No. 911,347.

Specification of Letters Patent.

Patented Feb. 2, 1909.

Application filed August 3, 1908. Serial No. 446,508.

To all whom it may concern:

Be it known that I, HILDEBERT VAN BUREN, a citizen of the United States, residing in the city and county of Philadelphia, State of Pennsylvania, have invented a new and useful Combined Gas-Burner and Water-Heater for Ranges, of which the following is a specification.

My invention relates to a new and useful gas burner and water heater for use on gas ranges whereby when the range is being used for cooking purposes or otherwise the water will be heated.

It further consists of a burner for gas ranges which has a supply pipe connected with the gas burner and a plurality of communicating chambers around the burner into which water can be conducted, said burner and water chambers being formed integral.

It further consists of other novel features of construction all as will be hereinafter fully set forth.

Figure 1 represents a plan view of a plurality of my combined burners and water heater showing the same suitably connected. Fig. 2 represents a sectional view of one of the burners on line $x-x$, Fig. 1, with the pipes removed. Fig. 3 represents a sectional view on line $y-y$, Fig. 1.

Similar numerals of reference indicate corresponding parts in the figures.

Referring to the drawings:—My invention is designed to provide that water will always be heated whenever the range is being used whereby it will be understood that when the range is being used for cooking it will at the same time heat the water.

In the drawings, I have shown a form for carrying out my invention which I have found in practice operates successfully but it will be understood that changes may be made in the parts, the arrangement of the same may be varied and other instrumentalities may be employed which will come within the scope of my invention and I do not therefore desire to be limited in every instance to the exact construction as herein shown and described but desire to make such changes as may be necessary.

In the drawings I have only shown the burners with the pipes for connecting the same with a suitable supply of gas or water but it will be understood that the other parts necessary for showing a complete and operative range have been omitted for the sake of clearness of illustration the outline of the

frame or body of the range being shown in dotted lines Fig. 1, which will give the substantial position of the burners with respect to the range.

1 designates a combined burner and water heater formed preferably of a circular body 2 forming an annular chamber 3 therein which preferably has the wings or off-set portions 4 of the body extending inwardly at intervals around the body 2 forming chambers 4' communicating with the annular chamber 3 and into which the water is adapted to be conducted. Between the annular chamber 3 and between the chambers 4 extends a web 5 which is preferably integral with the body 2 and is of any suitable thickness and formed on said web are the openings 6 forming the burners proper. Connected with or forming part of the web 5 is the downwardly extending pipe 7, it being noted that the said web 5 in which are the gas burners and the body portion 2 of the burner are preferably formed integral.

8 designates a disk which is preferably so dish-shaped and which is provided with a suitable opening adapted to receive the pipe 7, said disk having connected or integral therewith a gas and air inlet pipe 9 which is adapted to be suitably connected with a suitable source of gas and air supply to form the Bunsen flame. The upper edge of the disk is provided with a flange 10 which is adapted to seat a shoulder 11 formed on the lower wall of the body 2 so that said disk 8 closely engages the body and forms a gas chamber between said body and said web with which chamber the openings 6 communicate and any improper escape of the gas and air directed through pipe 9 into the chamber between the disk 8 and the burner plate 6 will be prevented by the engagement of the parts.

Any suitable means for holding the plate in position may be employed and in the drawings I have shown the lower end of the pipe 7 threaded as at 12 and the nut 13 mounted on said pipe which can be screwed up against a suitable washer 14 for holding the parts in proper position.

A suitable portion of the web 5 is cut away as at 15 providing openings leading to the atmosphere which serve as air vents and which are more clearly seen in Fig. 3.

16 designates a supply or inlet opening in the body 2 which is adapted to be connected with a suitable pipe in order that the water

may be fed into the water chamber, and 17 designates a discharge opening adapted to be connected with a suitable pipe for discharge of the water from the water chamber.

5 I preferably mount the burners in the manner shown in Fig. 1 in which 18 designates a waterpipe connected with the supply opening 16 of the first burner and connect the discharge opening 17 of the first burner with 10 inlet 16 of the next adjacent burner by means of a pipe 19 and so on around the gas range, 20 designating the final discharge pipe of the series which conducts the water to any suitable point.

15 21 designates the gas pipes which are connected with the gas inlet pipe 9 of the burners.

Water will be directed from a suitable supply through pipe 18 into the water chamber and all the burners having been ignited the water will first be heated in the first burner then passed to the next and so on around the range being further heated until it finally passes from the pipe 20 to a suitable point.

It will of course be understood that if all of the burners are not ignited that the water will be heated in the burners that are lighted and will pass through the others in the manner of the usual hot water circulation. It will be further understood that the extensions 4 of the body 2 may be dispensed with in some instances in which event I provide the annular chamber 3 with a web 5 therebetween in which are the burners proper so that the water in the chamber will be thoroughly heated.

From the above it will be evident that I have a combined burner and water heater in 40 which I provide a water chamber and a burner which is adjacent the water chamber and which if desired has portions thereof extending between extensions of the water chamber so that the water will be very thoroughly heated each time that the range is used.

It will be seen that the burner and water chamber are preferably integral or connected so the same may be removed and replaced by 50 another burner by simply unscrewing the pipe connection and it will be further understood that if desired I may introduce the water or the gas in a different manner from that shown in the drawings it only being necessary to supply the water and the gas in any suitable manner.

Having thus described my invention, what I claim as new and desire to secure by Letters Patent, is:—

60 1. In a device of the character described, an annular water chamber with integral web

and depending tube, said web having openings therethrough, and a gas chamber formed beneath said web and receiving said tube and secured to said water chamber. 65

2. In a device of the character described, an annular water chamber, a web integral therewith and having openings therethrough, and a gas chamber secured beneath said water chamber, said water chamber having 70 air vents in said web beyond the periphery of the gas chamber.

3. In a device of the character described, an annular water chamber, a web integral therewith and having gas burners therein, 75 and a removable plate forming a gas-tight gas chamber with the walls of the chamber and web.

4. In a device of the character described, an annular water chamber, a web integral 80 therewith and having gas burners therein, a removable plate forming a gas-tight gas chamber with the walls of the water chamber and web, and means for holding said plate in proper position.

5. In a device of the character described, a water chamber, a web integral therewith having gas burners therein, a pipe connected with said web, a plate movably mounted on said pipe and forming a gas-tight chamber with the walls of said water chamber and said web, and means for conducting gas and air into said chamber. 90

6. In a device of the character described, a water chamber having wings extending 95 inwardly therefrom and gas burners integral with said chamber and extending between said wings, said burners having air vents outside the periphery of the same.

7. In a device of the character described, 100 a water chamber, wings extending inwardly therefrom, a depending tube and a web integral with said chamber and said wings extending therebetween and having gas burners therein, a plate having an opening 105 receiving said tube and suitably supported and forming a gas chamber, and means for conducting gas and air into said chamber.

8. In a device of the character described, 110 a water chamber, inlet and outlet openings therefor, gas burners integral with said water chamber, a plate forming a gas chamber, means embodying a tube integral with the water chamber for supporting said plate in proper position, and means for conducting air and gas into said gas chamber. 115
